UNITED STATES PATENT OFFICE.

LUTHER H. GRIFFITH, OF SEATTLE, WASHINGTON.

HYDRAULIC CONVEYER.

No. 890,139.

Specification of Letters Patent.

Patented June 9, 1908.

Application filed June 24, 1907. Serial No. 380,472.

To all whom it may concern:

Be it known that I, LUTHER H. GRIFFITH, a citizen of the United States, residing at Seattle, in the county of King and State of Washington, have invented certain new and useful Improvements in Hydraulic Conveyers, of which the following is a specification, reference being had therein to the accompanying drawings.

10 This invention relates to improvements in hydraulic conveyers.

The principal object of the invention is the provision of means whereby a single pipe line is capable of receiving charges of excavated material at various points throughout its length without resorting to open sluiceways where the water pressure is not so effective as in pipes and unavailable where a conveyer is to be laid in ascending slopes toward the 20 delivery end.

A further object is the provision of means supplementing the power of a main stream in a hydraulic conveyer in order to add to the force of the latter in situations where the 25 duty is excessive and also to compensate for the retarding effect ensuing from the supply of fresh charges of excavated material intermediate the length of the pipe line.

With these and other ends in view the 30 invention consists in the novel construction, adaptation and combination of devices, as will be hereinafter described and claimed.

In the drawings, where similar reference characters designate corresponding parts in 35 all of the views, Figure 1 is a plan view of devices embodying my invention and shown applied to a pipe conduit; Fig. 2, an end view of the same; and Fig. 3 is a longitudinal sectional view.

40 The numeral 5 represents a pipe of suitable size and material for conveying excavated earth through the agency of a stream of water. At the top of the pipe is an aperture 6 through which is protruded the delivery end 45 of the charging hopper 7 and a water injection nozzle 8.

The hopper is formed adjacent of its bottom with marginal flanges 9 which are curved or otherwise formed upon their undersides to 50 conform with the peripheral surface of the pipe. At the lower forward end of the hopper is an opening 10 through which charges of dirt are deposited from the hopper into the pipe, and provided for such opening is a gate 55 11 adapted to be adjusted to close the opening, more or less, according to the quantity

and character of the material which is to be supplied therethrough. This gate is desirably seated upon the sloping front wall 7' of the hopper and is retained against being unseated by having its lateral edges housed in guideways formed by strips 12. The opening and closing movements of the gate are effected by a screw 13 rotatably mounted in bearings 14 of the hopper and engages a female screw provided in a lug 11' formed or provided on the gate and extending through an elongated slot 15 of said hopper wall. The said injection nozzle is screwed upon or otherwise detachably connected to a centrally 70 disposed branch 16 of passageways 16' provided to the rear of the sloping back wall 7" of the hopper, and such passageways extend transversely through the side wall 7'" where they terminate in screw - threaded 75 bosses 17. These bosses are adapted for connection by suitable coupling with lengths of hose which lead from a source of water supply; or where one or both of the bosses are not to be utilized, a cap, such as 18, Fig. 2, 80 may be used to close the same.

The operation of the invention may be explained as follows: Assuming that the pipe 5 is being employed in conveying dirt therethrough by the agency of water and in the 85 direction indicated by the arrow Y in Fig. 3; by charging the hopper 7 with dirt and opening the gate 11 the dirt will be deposited within the pipe and in so doing encounters the water which is injected through the nozzle 8, whereby it is impelled forwardly without retarding the flow ensuing within the pipe. The water thus injected also assists the power already acting within the pipe to accelerate the motion and may be resorted 90 to in such a capacity even when no dirt is being fed through the hopper, as may often-times be done when the work is excessive and in places where the pipe as laid inclines upwardly toward its delivery end.

100

What I claim as my invention, is—

1. The combination with a pipe and a hopper having a discharge opening communicating with the interior of the pipe, of means to close such opening, and means for introducing a jet of water within the pipe and to the rear of said opening.

105

2. The combination with a pipe, of a hopper provided with an opening in its bottom, a gate for closing said opening, means for adjustably moving said gate, a nozzle arranged within the pipe and directed across the bot-

110

tom of the hopper opening, and means communicating with said nozzle for conducting water to the latter.

3. The combination with a pipe, of a hopper provided with an opening in its bottom, a gate for closing said opening, said gate being provided with an internally threaded lug, a screw engaging said lug, a nozzle arranged within the pipe and directed across the bottom of the hopper opening, and means communicating with said nozzle for conducting water to the latter.

4. The combination with a pipe conveyer, of a hopper mounted thereon and having a discharge opening through which excavated material is deposited within the pipe, and means carried by the hopper for introducing a jet of water within the pipe. 15

In testimony whereof I affix my signature in presence of two witnesses.

LUTHER H. GRIFFITH.
